US00D959680S

(12) **United States Design Patent** (10) Patent No.: **US D959,680 S**
 Canepele et al. (45) Date of Patent: ** *Aug. 2, 2022

(54) **ADHESIVE BANDAGE WITH DECORATED PAD**(71) Applicant: **Johnson & Johnson Consumer Inc.**, Skillman, NJ (US)(72) Inventors: **Leonardo Canepele**, Jacareí (BR); **Andre Narcizo**, São José dos Campos (BR); **Paulo Cesar de Godoy Oriani**, Itatiba (BR); **Carmine Rizzo**, Port St. Lucie, FL (US); **Andre Luiz Santos**, São José dos Campos (BR)(73) Assignee: **Johnson & Johnson Consumer Inc.**, Skillman, NJ (US)

(*) Notice: This patent is subject to a terminal disclaimer.

(**) Term: **15 Years**(21) Appl. No.: **29/725,470**(22) Filed: **Feb. 25, 2020****Related U.S. Application Data**

(62) Division of application No. 29/643,727, filed on Apr. 11, 2018, now Pat. No. Des. 879,973.

(51) **LOC (13) Cl.** ..... **24-04**(52) **U.S. Cl.**USPC ..... **D24/189**(58) **Field of Classification Search**

CLAIM

We claim the ornamental design for an adhesive bandage with decorated pad, as shown and described.

DESCRIPTION

FIG. 1 is a top perspective view of the present invention; FIG. 2 is a top view of the adhesive bandage with decorated pad depicted in FIG. 1; FIG. 3 is a left side view of the adhesive bandage with decorated pad depicted in FIG. 1; FIG. 4 is a bottom view of the adhesive bandage with decorated pad depicted in FIG. 1; FIG. 5 is a right side view of the adhesive bandage with decorated pad depicted in FIG. 1; FIG. 6 is a front side view of the adhesive bandage with decorated pad depicted in FIG. 1;

FIG. 7 is a back side view of the adhesive bandage with decorated pad depicted in FIG. 1; FIG. 8 is a top perspective view of a second embodiment of the present invention; FIG. 9 is a top view of the adhesive bandage with decorated pad depicted in FIG. 8; FIG. 10 is a left side view of the adhesive bandage with decorated pad depicted in FIG. 8; FIG. 11 is a bottom view of the adhesive bandage with decorated pad depicted in FIG. 8; FIG. 12 is a right side view of the adhesive bandage with decorated pad depicted in FIG. 8; FIG. 13 is a front side view of the adhesive bandage with decorated pad depicted in FIG. 8; FIG. 14 is a back side view of the adhesive bandage with decorated pad depicted in FIG. 8; FIG. 15 is a top perspective view of a third embodiment of the present invention; FIG. 16 is a top view of the adhesive bandage with decorated pad depicted in FIG. 15; FIG. 17 is a left side view of the adhesive bandage with decorated pad depicted in FIG. 15; FIG. 18 is a bottom view of the adhesive bandage with decorated pad depicted in FIG. 15; FIG. 19 is a right side view of the adhesive bandage with decorated pad depicted in FIG. 15; FIG. 20 is a front side view of the adhesive bandage with decorated pad depicted in FIG. 15; FIG. 21 is a back side view of the adhesive bandage with decorated pad depicted in FIG. 15; FIG. 22 is a top perspective view of a fourth embodiment of the present invention; FIG. 23 is a top view of the adhesive bandage with decorated pad depicted in FIG. 22; FIG. 24 is a left side view of the adhesive bandage with decorated pad depicted in FIG. 22; FIG. 25 is a bottom view of the adhesive bandage with decorated pad depicted in FIG. 22; FIG. 26 is a right side view of the adhesive bandage with decorated pad depicted in FIG. 22; FIG. 27 is a front side view of the adhesive bandage with decorated pad depicted in FIG. 22; FIG. 28 is a back side view of the adhesive bandage with decorated pad depicted in FIG. 22; FIG. 29 is a top perspective view of a fifth embodiment of the present invention; FIG. 30 is a top view of the adhesive bandage with decorated pad depicted in FIG. 29; FIG. 31 is a left side view of the adhesive bandage with decorated pad depicted in FIG. 29; FIG. 32 is a bottom view of the adhesive bandage with decorated pad depicted in FIG. 29; FIG. 33 is a right side view of the adhesive bandage with decorated pad depicted in FIG. 29; FIG. 34 is a front side view of the adhesive bandage with decorated pad depicted in FIG. 29; FIG. 35 is a back side view of the adhesive bandage with decorated pad depicted in FIG. 29; FIG. 36 is a top perspective view of a sixth embodiment of the present invention; FIG. 37 is a top view of the adhesive bandage with decorated pad depicted in FIG. 36; FIG. 38 is a left side view of the adhesive bandage with decorated pad depicted in FIG. 37;

FIG. 39 is a bottom view of the adhesive bandage with decorated pad depicted in FIG. 38;

FIG. 40 is a right side view of the adhesive bandage with decorated pad depicted in FIG. 39;

FIG. 41 is a front side view of the adhesive bandage with decorated pad depicted in FIG. 40; and,

FIG. 42 is a back side view of the adhesive bandage with decorated pad depicted in FIG. 41.
